PORTABLE ROOF FOR OPEN-HEARTH FURNACES

Filed Aug. 27, 1947

FIG. 1.

FIG. 2.

FIG. 3.

INVENTOR:

JACK A. McDONALD,
Donald G. Dalton
HIS ATTORNEY.

UNITED STATES PATENT OFFICE

2,550,078

PORTABLE ROOF FOR OPEN-HEARTH
FURNACES

Jack A. McDonald, Duluth, Minn.

Application August 27, 1947, Serial No. 770,780

3 Claims. (Cl. 110—99)

1

This invention relates to open hearth furnace roofs and particularly to roofs formed as replaceable sectional units.

An object of the invention is to provide furnace roof structures formed as individually replaceable, sectional units of improved design, wherein the arched brickwork is suspended from frames removably supported directly on the buckstays.

A further object of the invention is to provide improved roof structures as set forth wherein the framework remains a part of the furnace after installation of the roof and may carry other furnace elements, such as a door cable sheave or coolant pipes.

A further object of the invention is to provide improved roof structures replaceable in sections as pre-constructed units, but accessible for minor repairs without replacement of an entire section.

In accomplishing these and other objects of the present invention, I have provided improved structural details, a preferred form of which is shown in the accompanying drawing, wherein:

Figure 1 is an end elevational view of an open hearth furnace having roof structure embodying features of the present invention, a wall of the furnace being omitted;

Figure 2 is a top plan view of a single roof unit constructed as shown in Figure 1; and

Figure 3 is a side elevational view of the roof unit.

Referring more in detail to the drawing:

In Figure 1 there is shown an open hearth furnace that includes side walls 10 and 11, a floor 12, buckstays 13 and 14 and a pre-constructed roof unit 15, of which there are several across the length of the furnace. The furnace also includes the usual end walls, burners, doors and other conventional elements, which per se are not involved in the present invention and are omitted for the sake of clarity.

In accordance with the present invention, roof unit 15 comprises a framework 16, preferably of steel, from which an arched roof 17 is suspended. Framework 16 includes uprights 18 and 19 spaced to register with buckstays 13 and 14. The lower ends of said uprights preferably are tapered as shown at 20 to interfit with notches 21 in the upper ends of said buckstays. The weight of the roof unit is thereby carried directly by the buckstays. The framework also includes upper horizontal end and side beams 22 and 23, respectively, a central beam 24 and diagonal braces 25. The various members are affixed together, as by welding, to form rigid framework open at the bottom.

2

A pair of longitudinally extending skewbacks 26 and 27 are fixed to uprights 18 and 19 and their inwardly directed faces are ribbed as shown in Figure 1. Skew bricks 28 and 29, having faces shaped to conform with the ribbed faces of said skewbacks, are fitted thereagainst. Bricks 30 to form arched roof 17 are placed in an arc between said skewbricks, being laid on a suitable arched form and wired in place. A clamp 31 is provided for holding the arch bricks from shifting endwise. Wood braces 32 may be provided to hold the arch bricks firmly in place while the pre-constructed unit is lifted to the furnace top.

A lifting eye 33 is secured to central beam 24 and is adapted to be engaged by a crane hook 34 for lifting and placing the roof unit. A sheave 35 may be mounted by suitable bearings on the framework for carrying a door cable. A coolant pipe 36 may also be carried by the framework, Figures 2 and 3.

According to the present invention, an open hearth roof is made up of several units constructed as described and placed end to end. When a roof section is damaged to the extent that replacement is necessary, the old section is removed and a new section lifted in place by suitable mechanical handling means that engage lifting eye 33. The form on which bricks 30 are laid either can be removed readily or left in place and burned on operation of the furnace. Framework 16 remains as a permanent part of the furnace structure. On furnace operation the brickwork becomes fused together and is supported by suspension from the framework.

It is seen that one or more roof sections can readily be replaced individually with a minimum of interruption of furnace operation. Also the brickwork in the roof is accessible for minor repairs that do not necessitate replacement of an entire section.

While I have shown and described only a single embodiment of the present invention, it is apparent that modifications may arise. Therefore I do not wish to be limited by the disclosure set forth, but only by the scope of the appended claims.

I claim:

1. In a furnace having walls and upright buckstays, a roof structure comprising a plurality of sectional units arranged end to end across the length of the furnace, said units each including framework having uprights, end and side beams and diagonal braces, said uprights removably resting on said buckstays in vertical alignment therewith for supporting the unit directly on the

buckstays, interfitting means on the lower ends of said uprights and on the upper ends of said buckstays for retaining them in vertical alignment, a pair of skewbacks, one of which bears against the uprights on each side of said framework, skew bricks fitting against said skewbacks, and arched brickwork extending across the sectional unit and bearing against said skew bricks, the units being individually removable and replaceable.

2. In a furnace having walls and upright buckstays, a roof structure comprising a plurality of sectional units arranged end to end across the length of the furnace, said units each including a rigid framework having uprights at each side spaced similarly to the furnace buckstays, end and side frame members fixed to the upper portions of said uprights, and diagonal braces fixed to said end and side frame members and said uprights, said uprights removably resting on said buckstays in vertical alignment therewith and forming extensions of the buckstays for supporting the unit directly on the buckstays, interfitting means on the lower ends of said uprights and on the upper ends of said buckstays for retaining them in vertical alignment, a pair of skewbacks, one of which bears against the lower portions of the uprights on each side of said framework above said interfitting means, skew bricks fitting against said skewbacks, and arched brickwork extending across the sectional unit and bearing against said skew bricks, the units being individually removable and replaceable.

3. In an open hearth furnace having walls and

upright buckstays, a roof structure comprising a plurality of sectional units arranged end to end across the length of the furnace, said units including framework having uprights, end and side beams, and diagonal braces, said uprights being in vertical alignment with said buckstays and forming extensions thereof for supporting the unit directly on the buckstays, interfitting means on said buckstays and framework uprights for retaining the uprights in alignment with the buckstays, skewbacks extending along the sides of the framework inside said uprights and having ribbed faces directed inwardly, skew bricks secured against said skewbacks and having faces that conform with said ribbed faces, and arched brickwork between said skew bricks, being thereby supported by suspension from said framework, the units being individually removable and replaceable.

JACK A. McDONALD.
